CASKET TABLE FOR HEARSE

Earl L. Schofield, Freeport, Ill., assignor to Henny Motor Company, Freeport, Ill., a corporation of Delaware

Application October 23, 1936, Serial No. 107,259

3 Claims. (Cl. 296—16)

This invention relates to hearses, and is particularly concerned with an improved casket table therefor.

The principal object of my invention consists in the provision of protective hand grips on the corners of the table designed with a hand well affording a firm grip for the hand from any angle, and at the same time protection for the fingers against extension below the table so as 10 not to scuff on the floor or get pinched between the floor and table. An important feature in this connection is the incorporating of each of these hand grips in one-piece L-shaped heavy corner plates with one branch forming a support for an 15 end roller and the other branch providing the handle, and incidentally also a mounting for a side guiding bier pin in a certain spaced relation to the end roller. These corner plates also afford good reinforcement for the table.

20 The invention is illustrated in the accompanying drawings, in which—

Figure 1 is a plan view of my improved casket table;

Fig. 2 is a plan view of one of the corner plates, 25 on a larger scale, showing the improved end roller and corner handle with the bier pin removed to disclose its mounting;

Fig. 3 is a side view of Fig. 2;

Fig. 4 is a horizontal section on the line 4—4 30 of Fig. 3 looking upwardly;

Fig. 5 is a longitudinal section on the broken line 5—5 of Fig. 2, on a somewhat enlarged scale, with an intermediate portion of the roller and corner plate broken away to permit showing the 35 construction on this scale;

Fig. 6 is a cross-section on the line 6—6 of Fig. 2, on the same scale as Fig. 5;

Fig. 7 is a longitudinal section through one of the intermediate rollers taken on the line 7—7 40 of Fig. 1, with an intermediate portion of the roller broken away to permit showing the construction on this scale, and

Fig. 8 is a cross-section on the line 8—8 of Fig. 7.

45 The same reference numerals are applied to corresponding parts throughout the views.

Referring to Fig. 1, the casket table 9 is intended for use in a side delivery hearse in which the table moves forwardly and to either side for 50 loading and unloading, and is also usually movable rearwardly from the hearse for the same purpose, such hearses being known as the three-way service type. In loading and unloading, pins 10 in the side plates 11 serve mainly as guides, and when the casket has been placed on the

table approximately centrally, other bier pins 10 are entered in the proper holes in plates 12 at opposite ends of the table to serve as stays and prevent objectionable movement of the casket. In accordance with another application Serial No. 241,501, filed November 21, 1938, the twelve rollers 13 mounted on the table in pairs in longitudinally spaced relation are all of rubber of medium softness, and these support the casket for smooth and silent movement onto and off the table, the rumbling noise which otherwise accompanied the movement of the casket over the old style metal rollers being thereby eliminated. Furthermore, due to the yield of the rubber, the casket in rolling thereon is prevented from slipping sideways. The yield of the rubber also is an important factor in anchoring the casket on the table; whereas it was necessary to have at least four bier pins in contact with the casket, two at opposite ends and the other two on opposite sides, two pins, one at each end, to prevent endwise movement, are adequate with the present invention. As stated before, the pins 10 in side plates 11 serve mainly as guides when loading and unloading the casket; there is no need to have them contact the sides of the casket, inasmuch as the rubber rollers 13 will not permit side slipping. The rollers 13, as will further appear later, are all equipped with special softer rubber end thrust bearings 14 to cushion the 20 side motion of the rollers. This eliminates any tendency toward chattering, if there happens to be a certain amount of lateral movement of the casket relative to the rollers, in loading and unloading, and by avoiding chattering I also obviate the danger of any squealing noise, which would, of course, be particularly objectionable in a structure of this kind. Smooth and silent operation, as well as an increased degree of safety and protection for the casket, are secured by the use of these rubber rollers 13 in place of metal rollers. The rubber moreover presents a wear resisting surface, so that these rubber rollers will 25 preserve a good appearance indefinitely and not soon show signs of service like the metal rollers 30 did.

Skid plates 15 are provided in the space between the rollers 13 for protection of the table surface. They prevent scraping or gouging of the table in case the casket is lowered unevenly onto the table, or is removed carelessly or awkwardly. The skids extend up close to the rollers 13 so that the edges of the casket will not be apt to come in contact with the table hardware. The casket will ordinarily be supported on the rollers 35 40 45 50 55

entirely, clear of the skids, but of course, when, due to long service and the effect of age on the rubber, or in cases where unusually heavy caskets are supported thereon, the rollers have the casket sink rather deeply in the rubber there-of, especially while the hearse is in motion, the skids 15 will serve positively to limit such im-
pression by contact at one or more points with the bottom of the casket. One or more skid plates will serve a similar purpose when the casket happens to be lowered unevenly onto the table, placing more than the customary amount of weight on one or more of the rubber rollers.

Corner plates 16 form the subject matter of this application and are of heavy L-shaped construction and fastened securely to the four corners of the table and provide on one branch 17 of each plate a support for a roller 13 and on the other branch 18 a handle 19 and a mounting 20 for a side-guiding bier pin, along with a specially constructed well 21 in connection with the handle 19. The roller support 17, as clearly appears in Figs. 1, 2, 3 and 6, mounts the roller in the end of the table with its axle shaft 22 located as close 25 to the edge of the table as possible, so that the roller actually stands out from the end of the table and is bound to be the first to be engaged by the casket in loading and the last to be engaged in unloading. This is quite an advantage, particularly in the handling of heavy caskets, which, when the rollers were mounted at a certain distance from the end of the table, necessitated great care on the part of the pall-bearers in setting the end of the casket down onto the table to be sure it was riding on the rollers and not resting directly on the table. With the first rollers located at the extreme end of the table, that difficulty is avoided, because the usable length of the table is proportionately increased 40 to the extent that the location of the rollers has been advanced to the ends of the table.

All of the rollers 13 have the tubular rubber bodies thereof molded and bonded to tubular steel cores 23 by vulcanizing, the cores being brass plated to insure a good bond with the rubber. Bushings 24 entered with a press fit in the opposite ends of the core of each roller receive the axles 22, so that the rollers turn rather freely on these axles. The axles in the case of all of 50 the intermediate rollers of the table are mounted, as shown in Figs. 7 and 8, namely, in rectangular plates 25, with some end plates 26 fastened in place with screws 27 from beneath serving to clamp the ends of the axle. The table is recessed, as at 28, to accommodate the plate 25, and recessed still deeper, as at 29, to accommodate the roller 13. Screws 30 fasten the plate 25 in place and are entered in holes 31 which are filled with rubber plugs 32, which, being black 55 to match the finish of the top of the plate 25, are not at all noticeable.

The end rollers on the corner plates 16 are mounted, as illustrated in Figs. 2, 5 and 6. A well 33 is formed in the corner plate itself to accommodate the roller, and at opposite ends of this well are aligned holes 34 and 35 into which the axle 22 is entered from the end of the branch 17 and, of course, through the roller. Then set screws 36 entered in tapped holes 37 from beneath the corner plate are tightened and serve to anchor the axle.

The end thrust bearings 14, previously mentioned, are of molded sponge rubber and are in the form of washers, as indicated in Figs. 5 and 75 7, assembled on the axles 22 at opposite ends of

the rollers. Each of these soft rubber washers is protected and backed up by a metal washer 38.

The handles 19 are formed mainly by a rib 39 cast integral with the rest of the corner plate, which is a die casting. Recesses 40 formed in the bottom of the rib 39 accommodate lugs 41 molded integral with a grip 42 which is of Bakelite or other suitable composition material, made to fit snugly on the exterior of the rib 39. Screws 43 entered through the lugs 41, from beneath, 10 and threaded in holes in the rib 39, hold the grip 42 in place. A wall 44 also cast integral with each corner plate is spaced from the rib 39 to define the hand well 21 therebetween, and this wall has an outwardly curved skirt portion 45 15 which, as shown in Fig. 5, forms a sort of baffle to deflect the ends of the fingers when the handle 19 is being grasped, and prevents one from getting the fingers under the table where they would be apt to be pinched if the table were 20 moved relative to the floor of the hearse. In other words, this curved apron 45 forms a shield for the fingers, so that one will not get the fingers scuffed or pinched through careless holding of the handle. The apron 45 predetermines how 25 the fingers must lie with respect to the handle, and it eliminates the danger of injury. It is clear in Figs. 1 to 3 that the baffle apron 45 is curved at one end through approximately 90° to follow the curvature of the handle 19 which has 30 approximately 90° curvature at the end to form a rounded corner on the table and permit grasping the handle from the side or end of the table with substantially equal facility.

In conclusion, it should be evident that the 35 corner plates 16, in addition to providing roller mountings, handles and bier pin supports, also afford good reenforcement for the table.

It is believed the foregoing description conveys a good understanding of the objects and advantages of my invention. While I have shown the rubber rollers 13 on a table 9, it should be understood that I may provide such rollers on the floor of an ordinary rear loading hearse to equal advantage. The appended claims have, therefore, 45 been drawn with a view to covering this and other legitimate modifications and adaptations of the invention.

I claim:

1. In a casket table for a hearse adapted to be 50 moved by hand to and fro over and in closely spaced relation to the floor of the hearse, a horizontally disposed handle plate adapted to be secured to the horizontal edge portion of the table, said plate being formed to provide a body portion 55 and an integral web portion disposed in spaced relation to the body portion but connected thereto at its ends, said web portion providing a hand grip adapted to be grasped from above when in substantially horizontal position on a casket table on a hearse, the body portion being formed to provide a substantially vertical wall inwardly spaced relative to the web portion sufficient to admit the fingers of a human hand grasping the hand grip in the manner stated, the lower portion of said wall being formed to provide an outwardly sloping surface, all portions of which are substantially in the same spaced relation to the hand grip as the vertical portion of said wall so as to cause the operator's fingers in grasping 70 the hand grip to bend to enclose the same, the lower portion of said wall being extended outwardly far enough in the direction of the hand grip to prevent extension of fingers straight downwardly behind the hand grip and projec- 75

tion thereof below the table, substantially as described.

2. In a casket table for a hearse, a combination handle plate and casket roller support adapted to be secured to a corner of said table, said plate being formed L-shaped to provide a handle portion on one branch and a casket roller support on the other branch in substantially right angle relation to the handle portion, the handle portion of said plate being formed to provide a body portion and an integral web portion disposed in spaced relation to the body portion but connected thereto at its ends, said web portion providing a hand grip adapted to be grasped from above when in substantially horizontal position on a casket table on a hearse, the body portion being formed to provide a substantially vertical wall inwardly spaced relative to the web portion sufficient to admit the fingers of a human hand grasping the hand grip in the manner stated, the lower portion of said wall being formed to provide an outwardly sloping surface, all portions of which are substantially in the same spaced relation to the hand grip as the vertical portion of said wall, the handle portion of said plate extending longitudinally relative to the table along the side thereof to the end, and the other portion of said plate extending along the end of the table so as to be adapted to support a casket roller, and an elongated casket roller disposed crosswise on the end of the table and supported on the last named portion of said plate.

3. Handle means for the corner portion of a casket table in a hearse, comprising a body providing an attaching portion adapted to be se-

cured to the horizontal edge portion of the table at the corner thereof and an elongated hand grip portion rigid therewith at its ends and disposed in spaced relation to said attaching portion to permit the operator grasping the same with the hand from above the table for movement of the table to and fro over and in closely spaced relation to the floor of the hearse, the hand grip having a straight portion substantially parallel to the edge of the table and an approximately 90° arcuate end portion for the corner of the table, the attaching portion being formed to provide a substantially vertical wall spaced inwardly relative to the hand grip so as to admit the fingers of the operator's hand therebetween in grasping the hand grip in the manner stated, the lower portion of said wall being formed to provide an outwardly sloping outer surface all portions of which are substantially in the same spaced relation to the hand grip as the vertical portion of said wall so as to cause the operator's fingers in grasping the hand grip to bend to enclose the same, the lower portion of said wall being extended outwardly far enough in the direction of the hand grip to prevent extension of fingers straight downwardly behind the hand grip and projection thereof below the table, substantially as described, said attaching portion having a straight portion parallel to the straight portion of the handle and an approximately 90° arcuate end portion for the corner of the table in inwardly spaced relation to the arcuate end portion of the hand grip.

EARL L. SCHOFIELD. 35
